UNITED STATES PATENT OFFICE.

FREDERICK J. VEITCH, OF NEW YORK, N. Y.

AEROPLANE.

1,258,279.

Specification of Letters Patent.

Patented Mar. 5, 1918.

Application filed April 15, 1912. Serial No. 690,686.

To all whom it may concern:

Be it known that I, FREDERICK J. VEITCH, a citizen of the United States, residing in the city of New York, borough of Manhattan, county and State of New York, have invented a certain new and useful Aeroplane, of which the following is a specification.

This invention is an aeroplane, and the objects are to attain stability and to steer or direct the aerocraft without resorting to moving parts such as warping planes and pivoted rudders.

It is well known that moving parts, similar to pivoted planes and pivoted steering rudders, employed in prior machines are, so to speak, sources of weakness owing to more or less frailty of construction and to their tendency to bend and break when subjected to wind pressure, particularly in case the craft is moving at high speed or is caught in a gale of wind.

According to this invention, one or more counter-balance weights are employed to secure stability of the craft and to control or steer said craft. It is preferred to position one weight below the bottom weight-carrying plane, and to mount or support said weight for movement in the direction of the length of said plane, suitable means being provided for shifting the weight and for controlling the position of said weight, whereby it may be moved at will either to the right or left of the central fore and aft line of the craft. The moving of said weight toward either end will cause weight-ed end to lower and opposite end to raise, the degree of tilt will increase with the moving of weight from the center of the fore and aft line of craft, the longitudinal position of the weight-lifting planes in reference to the horizon will at all times depend upon the position of said movable weight whereby aeroplane can be made to assume any desired angle and remain balanced at said angle until any desired turn is made. The aerocraft will always turn in a horizontal direction toward the lower end of weight-lifting planes.

At the rear of the weight-carrying planes is positioned a balancing plane or tail which, in contradistinction to prior pivoted and movable tails, is secured fixedly in position so as to occupy at all times a certain predetermined relation to the weight-carrying planes. Coöoperating with the weight-carry-

ing planes and with the tail plane is the other or second counterbalance weight, the latter being positioned for movement in the plane of the tail plane and below that of the upper weight-carrying plane, so that said second named weight moves about in the center of gravity of the width of aerocraft. Said weight is shiftable at will between the weight-carrying planes and the tail plane, and it is controlled in a manner to exert its ponderosity upon the craft so as to depress or elevate the tail plane, whereby said craft may be caused to ascend or descend according to the position of the weight relative to the tail plane and weight-carrying planes. The aeroplane will be constructed with the center of gravity well forward, so that while in normal horizontal flight the air craft will balance properly, with the weight located at about the center between the weight lifting planes and the tail. To increase the speed of air craft while in flight, the tail will naturally lower, and by moving the movable weight slightly forward the tail plane will resume its normal position. This weight acts as a stabilizer between the front and rear planes as well as for steering the air craft in vertical directions. It can readily be seen that the air craft can glide and move through space at various speeds with all planes positioned so as to give a minimum resistance to the air. Said weight might also be used on a tailless aeroplane having a front balancing plane, by utilizing weight between balancing plane and weight lifting planes.

Other features of the invention, and the advantages thereof, will appear in the course of the annexed detailed description taken in connection with the drawings.

In the accompanying drawings, I have illustrated one practical embodiment of the invention, but the construction shown therein is to be understood as illustrative, only, and not as defining the limits of the invention.

Figure 1 is a perspective view of an aerocraft embodying the present invention.

Fig. 2 is a vertical sectional elevation taken about centrally through the craft fore and aft thereof.

Fig. 3 is a detail sectional view illustrating one construction whereby the counterweight is supported for movement in a certain direction relative to certain planes of the aerocraft.

Fig. 4 is an end view of the construction shown in Fig. 3.

Fig. 5 is a view on an enlarged scale illustrating one device whereby the stabilizing 5 horizontal steering weight and the vertical steering weight are controllable from the aviator's station.

The aircraft shown in Figs. 1 and 2 of the drawings is of the type known as a biplane, embodying an upper weight-carrying plane A and a lower weight-carrying plane B, the two planes being of any usual or preferred construction, and connected together by vertical frame members *a*. As shown, 10 each weight-carrying plane is curved or arched in cross section, the two planes are of suitable length and width, and they are retained by the frame members *a* in predetermined fixed positions relative to each 15 other. The craft is intended to be equipped with an engine or motor of a suitable type, and with two or more propellers arranged and operating as is usual in biplanes, but as the motor and the propelling mechanism 20 may be usual in the art, and form no part of the present invention, it has not been considered necessary to illustrate or describe 25 the same.

The aviator's seat or station C is positioned on the frame work of the craft above 30 the lower weight-carrying plane B and about the center of length of said plane.

D is a balancing plane or tail plane positioned at the rear of the weight-carrying 35 planes, said tail plane occupying a substantially horizontal position intermediate the upper and lower weight-carrying planes and well to the rear thereof. This tail plane may be of any form or construction known 40 to those skilled in the art, but in contradistinction to the movable tail planes heretofore employed, the tail plane of my craft is secured in a fixed predetermined relation to the weight-carrying planes, it being understood that the tail plane is immovably 45 supported in operative position. As shown, the tail plane is arched in cross section and it is connected by suitable braces *b* with the frame work of the weight-carrying planes.

50 Positioned below the lower weight-carrying plane B is a track member E on which is supported a shiftable stabilizing and steering counterweight F. The track member E is shown in the form of a rod or truss bar positioned well below plane B, and at the rear thereof, said track member being substantially parallel to said plane B and extending in the direction of the length of said plane. Track member E is retained in 55 parallel position to the lower plane by vertical struts *e* depending from the rear part of the frame work, the ends *e'* of said track member being inclined upwardly and secured to the end portions of the lower plane B, as shown in Fig. 1.

The stabilizing and steering weight is supported in any suitable way upon the track member for movement in the direction of the length thereof, said weight being movable in a path substantially parallel to 70 the bottom plane B, and the movement of the weight being in the direction of the length of said plane. The weight may be mounted on or suspended from the track member as desired, but it is preferred to 75 provide said weight with a longitudinal passage *f* and with recesses *f'*, the latter accommodating suitable rollers *g* which are mounted in the weight for rotation freely therein. The track member E passes 80 loosely through the longitudinal passage *f* and below rollers *g*, whereby the rollers are adapted to rest upon the track member for supporting said weight upon said track member. It will thus be seen that the 85 weight is movable freely on the track member in the direction of the length thereof, and by passing the track member through the weight, the tendency of the weight to sway upon the track member is minimized. 90 The weight is adapted to be shifted in a direction lengthwise of the lower plane by any suitable operating and retaining means, but as shown in the drawings, said weight is provided at its ends with bails *h'*, to one 95 of which is connected an operating cord *i*, while a similar operating cord *i'* is connected to the other bail. The operating cords *i*, *i'* extend in opposite directions from the weight F, and they pass over suitable 100 direction pulleys *i²*, *i³* which are supported at the respective ends of the lower plane B. Said operating cords extend from the direction pulleys inwardly toward a winding pulley G which is secured firmly to a manually operable shaft H, said shaft being supported in suitable bearings *h²*, *h³* secured, on the frame work in such position that the hand wheel H' is convenient to the operator occupying the station C. One 110 cord *i* is coiled in one direction around the winding pulley, whereas the other cord *i'* is coiled in an opposite direction around the winding pulley, and thus the rotation of spindle H and winding pulley G in one direction 115 places tension upon one cord, as *i*, and relaxes the other cord *i'* for shifting the weight F in one direction along the track member E, but the rotation of the spindle and the winding pulley in an opposite direction places tension upon cord *i'*, and relaxes tension upon cord *i* for imparting movement to weight F in an opposite direction along track member E.

In the normal position of the stabilizing 125 and steering weight, it is retained by the operating cords in a position substantially at the middle of the craft and about midway between the ends of track member B. When it is desired to steer the craft around to the 130

right, the spindle H is rotated so as to shift the weight toward the right, said weight being of sufficient heaviness to depress the craft at the end portion thereof toward 5 which the weight is shifted, whereby the craft may be steered toward the right. For steering the craft toward the left the spindle is operated in a reverse direction so as to move the weight in an opposite direction, 10 and thus the weight-carrying planes at the opposite end of the craft are lowered for the purpose of steering the craft toward the left. Should the craft heel over or turn from its normal position by the 15 pressure of a sudden gust of wind, the effect is to impose the ponderosity of the weight upon the elevated end of the craft, and thus bring the craft back to a substantially normal position. It is thus apparent that the 20 weight F tends to automatically secure stability of the craft while in flight, and the movement of the weight in one direction or the other provides for the control or steering of the craft.

25 In addition to the foregoing mechanism for securing stability and the steering of the craft, another shiftable weight I is employed. This weight I is similar in construction to the weight F shown in Figs. 30 3 and 4, and it is supported upon a track member J, shown in Fig. 2 as a rod extending between the weight-carrying planes and the tail plane. Said track member is secured at its rear to the forward portion of 35 the tail plane, whereas the front part of the track member is secured to the frame work α intermediate the upper and lower weight-carrying planes A, B. The weight I is thus positioned for movement toward and from 40 the weight-carrying planes and the tail plane, and said weight is supported and moves at or about the center of gravity of the width of craft. The weight is movable upon track member J, and it is shifted and controlled by mechanism similar to the controlling 45 devices for the stabilizing and steering weight. As shown, a cord j is attached to the forward part of weight I and extends over direction rollers j' , j'' to a winding pulley 50 K, the latter being secured to an end portion of a tubular shaft K'. Said tubular shaft is fitted over the operating shaft H, and at one end of this tubular shaft is a hand wheel K'', the latter being positioned quite close 55 to hand wheel H' and operating shaft H, see Fig. 5. To the rear of weight I is attached another operating cord k which extends around direction rollers k' and j'' , said operating cord k being coiled on the wind- 60 ing pulley K in an opposite direction to that in which cord j is coiled on said pulley K. The tubular shaft may easily be rotated by the operator manipulating hand wheel K'', so that pulley K may be turned in one 65 direction or the other for the purpose of placing tension upon either of the operating cords j, k. It is evident that the rotation of the winding pulley K in one direction will exert tension upon the cord j, for the purpose of moving weight I toward the 70 weight-carrying planes and away from the tail plane, thereby imposing the ponderosity of weight I upon the forward part of the craft, which is so balanced that the re- 75 sult is to elevate the tail plane at the rear 75 part of the craft, in a manner to result in a descent of said craft. By turning the winding pulley K in an opposite direction, however, cord j is slackened and tension is placed upon cord k, as a result of which the 80 weight is moved rearwardly, away from planes A, B, and toward plane D, thus de- 85 pressing the tail plane at the rear part of the craft, in consequence of which the craft will be caused to ascend.

It is evident that hand wheels H', K'' may be operated independently by the aviator for the purpose of rotating the winding pulleys G, K separately, and operating the several cords in a manner to control the 90 position of the horizontal steering weight F and the vertical steering weight I. Should it become necessary the weights may be shifted simultaneously, but ordinarily it is sufficient to move the weights independently 95 of each other.

Having thus fully described the invention, what I claim as new, and desire to secure by Letters Patent is:

1. An aerocraft embodying a plurality of 100 weight-carrying planes, a balancing plane in the rear of said weight-carrying planes, said balancing plane occupying an immovable position with reference to said weight-carrying planes, a lateral stabilizing and 105 steering weight supported below the lower of said weight-carrying planes, means for controlling and adjusting the position of said weight with relation to said weight-carrying planes, a stabilizing vertical steer- 110 ing weight supported for movement between the weight-carrying planes and the balancing plane, and controlling means for shifting and retaining in position said vertical steering weight.
2. An aerocraft having independent slide- 115 able weights for steering the same in horizontal and vertical directions, in combination with two operating spindles one of which is tubular and incases the other, hand 120 wheels on said spindles, and operative connections between the spindles and said move- 125 able weights.
3. An aerocraft having movable weights for steering the same in horizontal and vertical directions, in combination with two operating spindles one of which is tubular and incases the other, hand wheels on said spindles, and operative connections between the spindles and said movable weights.

4. An aerocraft having movable weights for steering the same in horizontal and vertical directions, in combination with two operating spindles one of which is tubular and incases the other, hand wheels on said spindles, and running cords operated by the spindles and connected to said weights.
